US0D1016396S

(12) United States Design Patent (10) Patent No.: US D1,016,396 S
(45) Date of Patent: * Feb. 27, 2024

(54) PEDICURE DEVICE

(71) Applicant: John Mills Limited, London (GB)

(72) Inventor: Sarah Torrance, London (GB)

(73) Assignee: John Mills Limited, London (GB)

() Term: 15 Years

(21) Appl. No.: 35/514,717

(22) Filed: May 19, 2022

(80) Hague Agreement Data

Int. Filing Date: May 19, 2022

Int. Reg. No.: DM/221999

Int. Reg. Date: May 19, 2022

Int. Reg. Pub. Date: Jul. 15, 2022

(51) LOC (14) Cl. 28-03

(52) U.S. Cl.

USPC D28/58; D28/59
